UNITED STATES PATENT OFFICE

HERBERT AUSTIN, OF BROMSGROVE, ENGLAND

VEHICLE BODY HAVING A COLLAPSIBLE HEAD

Application filed September 18, 1930, Serial No. 482,769, and in Great Britain September 23, 1929.

This invention relates to the type of vehicle body having what is known as a "sunshine roof" that is to say a body having fixed cant rails at either side passing over the doors and windows and having a flexible cover acting as the roof and being adapted to be drawn back to the rear of the vehicle to open the top thereof when desired. In this type of vehicle body as heretofore constructed the fabric roof has been supported on transverse roof members which engage at their ends with the cant rails and are adapted to slide in relation thereto. These roof members or alternate roof members have been provided with endway projections to engage in a groove at the inner surface of the cant rail and all of such members when set up have passed beneath a retaining strip projecting inward from the cant rail.

According to one feature of the present invention, in lieu of projections from each or some of the roof members, a rib or longitudinal plate is arranged to extend inwards from the cant rail at each side of the vehicle and enter a groove in the end of each roof member or a groove carried thereby or in each alternate roof member, as the case may be. Preferably the plate passes under a portion of all the roof members; and alternate members may have each a plate screwed to its under side and cranked down to form the groove to receive the plate of the cant rail. There is preferably provided, at each side of the vehicle, an upper inwardly extending longitudinal rib or plate passing over the ends of the roof members; but this rib or plate is discontinued at or near the rear of the vehicle top to allow the roof members which have no end grooves to move upwards or outwards of the cant rails. This latter rib or plate may be constituted as an inward flange of a channel which is set in the cant rail and is open at the top to receive a bead at the edge of the fabric cover, the channel being utilized to drain water therefrom.

In applying the invention to a case where the cover is operated by the agency of a chain at either side guided in two channels open towards the inside and secured one above the other to the inner face of the respective

cant rail, the rib or plate which enters the grooves in the roof members may be inserted between the channels, and in either case may pass immediately beneath the drainage channel which carries the upper rib or plate. 55

According to another feature of the invention the longitudinal plate forming the said rib has a narrow downwardly extending flange at its inner or free edge and the cranking down of each of the plates of the roof members is sufficient to permit each plate to pass across under the said downward flange, and the inner edge of each plate is flanged upwards sufficiently to ensure that the end of a roof member will always keep in engagement with the rib of the cant rail. 60

According to another feature of this invention the end of each roof member has a vertical hole formed therethrough in which is placed a wad of felt soaked in oil or tallow, the felt preferably extending somewhat beyond the ends of the holes so as to keep the guide lubricated. 65

The invention is described with reference to the drawing herewith, of which:— 70

Figure 1 is a cross section through one of the cant rails of a vehicle body to which my invention is applied, and showing the end of one of the "fixed" transverse roof members, that is to say one of the members which always remain in engagement with the cant rail. 75

Figure 2 is a section of another part of the cant rail and showing the end of one of the roof members which are "loose", that is to say capable of moving away from the cant rail when the roof fabric folds or pleats up at the rear of the vehicle; and, 80

Figure 3 is a cross section through a cant rail of a vehicle in which the roof fabric is moved through the agency of chains guided in channels secured to the inner face of the cant rail. 85

Referring first to Figure 1, A is the cant rail having a channel secured within a rabbet at its upper inner corner. The channel has an outward flange b passing over the top of the cant rail and secured thereto by wood screws. The channel has also an inward flange b' which passes over the ends of the 90

100

transverse roof members C to which latter the roof fabric D is secured. The flange *b'* is discontinued at the rear of the vehicle to allow the "loose" transverse roof members to move away from the cant rail as the roof fabric folds up or pleats. F is a continuous length of coil spring carried in a fabric sheath *f* stitched to the under surface of the roof fabric. This coil spring is attached also to the front transverse roof member and serves as the means by which the fabric and the rest of the transverse members are moved back. G is a metal strip clamped between the channel base and the cant rail and extending along the whole length of the cant rail and projecting under the ends of the transverse roof members and providing a support therefor. The transverse member C shown in Figure 1 is a "fixed" member and carries a plate H secured to its under surface and being cranked down to pass under the plate G thus to keep the said transverse member always in its relation to the cant rail even when the roof fabric is folded up. It will be seen that the plate G has a downward flange *g* at its inner edge and that the plate H is turned up at *h* so as to come behind the flange *g*. This limits the degree of movement of the transverse member C. J is a piece of grease soaked felt or other fabric lying within a vertical hole formed in each transverse member near its end, said grease serving to lubricate the flange *b'* and strip G.

In Figure 2 the construction is the same except that there is no strip H, so that the transverse member C' is "loose" that is it can move away from the cant rail as soon as it has moved back sufficiently to be clear of the flange *b'*.

Referring to Figure 3, which illustrates the application of the invention to a case where the front transverse member is moved through the medium of a chain, not shown, but guided in channels K, a strip of metal G' (corresponding to the strip G in Figure 1) is clamped between the channels and extends inward under the ends of the transverse members C². Each alternate member C² is provided with a plate H' secured to its under surface and being cranked down so as to pass beneath the plate G' thus to constitute the member C² as a "fixed" member. The other transverse members are without the plate H' and are "loose" members. The plate G' may, if desired, be provided with a downward flange and the plate H' with an upturned ledge similarly as in Figure 1.

Having fully described my invention what I claim and desire to secure by Letters Patent is:—

A roof of a vehicle body comprising fixed cant rails one at each side passing over the doors and windows of the vehicle, a flexible roof cover adapted to be drawn back to the rear of the vehicle to open the top thereof,

transverse roof members supporting said fabric and having their ends in slidable relationship to the cant rails, a rib in respect of each cant rail extending inwards therefrom, a downward flange on said rib, a plate secured to the under surface of the respective ends of each said roof member and together with said ends forming a groove with which said rib engages, said rib supporting the respective ends of said roof members, and an upward flange on said plate adapted to come behind said downward flange of said rib.

In witness whereof I have hereunto signed my name this fifteenth day of September 1930.

HERBERT AUSTIN.
